BLADED DISK FOR RADIAL FLOW ROTARY MACHINES

Ulrich Meininghaus, Mulheim-Ruhr, Germany;
vested in the Alien Property CustodianApplication November 16, 1940, Serial No. 365,892
In Germany November 21, 1939

6. Claims. (Cl. 253—39)

The present invention relates to the bladed wheel construction of rotary machines, and especially of radial flow steam and gas turbines.

It is the general object of the invention to provide an improved disk for radial flow engines which is capable of withstanding axial thrusts even if at the same time a great temperature drop exists between both sides of the inner part of the wheel, and in particular a wheel which keeps its strength when the connection of wheel and shaft is elastic in order to allow for free expansion and contraction of the wheel due to temperature changes. Other, more specific objects of the invention will appear from the detailed description hereinafter.

The accompanying drawings illustrate by way of example different embodiments of the invention. Figs. 1 to 3 of the accompanying drawings are vertical fragmentary sections through three different forms of bladed disks for a radial flow steam turbine constructed according to the invention; Fig. 4 is a section through the whole turbine; Fig. 5 is an enlarged fragmentary vertical section through the central portion of a modified form of bladed disk.

In Fig. 1, the wheel 1 is shrunk on the shaft 2 at 3 and 4 by means of the elastic ring 17. The end of the ring 17 shrunk at 3 is pressed against the shoulder 5 of the shaft 2 by the thrust of the wheel 1. The nut 7 is an additional safeguard to hold the wheel in place. The rings 3r—19r are cut from the wheel leaving the webs 2s—18s between the rings. Especially the inner ring 3r, but also the adjacent rings 5r, 17r, etc., would take an oblique position in cases of wheels with undivided rings and webs as the steam entering at the left from the center is considerably hotter than the steam leaving inwardly at the right. The right end of the rings would be colder than the hot left end, and therefore the diameter of the right end will shrink in relation to the diameter of the left end. The temperature of the ring gradually decreases by reason of the heat flow from the left to the right and the whole ring takes an oblique position. On account of the oblique position of the rings, the disk itself takes also an oblique position which is further increased by the steam pressure exerted on one side of the disk. To diminish this obliquity, I cut a notch 20 with a saw along the median plane 50 of the wheel. This notch, being filled with an insulating layer of the driving medium increases the resistance to the flow of heat in such a way that the degree of obliquity of the rings is limited to non-dangerous values. That the notch 20 of 55

Figure 1 does not prevent the flow of heat along the ring 17 is no disadvantage as this ring represents an elastic joint between wheel and shaft the task of which is not to strengthen the disk. 5 It is only of advantage that the stresses of this elastic joint are relieved by the flow of heat along it and by the corresponding obliquity.

Fig. 2, to which the same reference numerals apply, illustrates a construction with two entirely 10 separated and then assembled halves of the wheel. The half 21 is connected with the half 1 by means of the elastic joint 22 and the calking wire 23. The torque of the half 21 is transferred to the half 1 through inter-engaging notches and 15 projections 24. The hub consisting of the rings 1r and 3r and web 2s carries both halves.

Fig. 3 shows a construction especially adapted for high steam pressures. The steam enters the blading 32 at the inner diameter and flows from the outer circumference of this blading to the blading 33 which is traversed inwardly. To restrict the flow of heat and to secure a freedom of expansion the wheel has been divided into parts 34 and 35. Difficulties arise in joining the two 20 halves in a sufficiently elastic way and keeping the joint at the same time absolutely tight at high steam pressure and temperature. I provide for this purpose an elastic member 36 of circular cross section. This elastic member I fasten to the hub of the wheel 31 by calking in the end 37 thereof in a suitable notch with a soft wire 38, and fasten it also to the inner part of the half 34 by inserting the end 39 of the member in a notch the wall 40 of which is expanded to enlarge its 25 diameter by a special tool. The main task of the elastic member 36 consists in bridging the variations in diameter occurring between the two halves of the wheel due to differences in the mean temperature or centrifugal forces. As the end 37 of the member extends in a radial direction, any variation in diameter of this end causes a rolling action inside the area of the circumference. This rolling action is similar to the winding of the spring of a watch and gives rise 30 to a comparatively equal distribution of the deformations across the total cross section of the circumference and avoids any dangerous local rise of the stresses at the points where the ends are clamped.

The rolling action will always be obtained when at least one end of the circular cross section to which the circumference of the annular elastic member is shaped to withstand the pressure runs at an angle of less than 45° to the direction in which the moving of said end is ef- 35

fected. The elastic member may in addition allow for small movements in other directions. It is well known how high a degree of deformation is safely allowable with spiral wound springs. In addition, the tangential stresses occurring in the annular elastic member exert a further equalizing influence.

The steam turbine which Fig. 4 shows in section makes use of the present invention for the double impinged wheel in the center of the machine. The shaft of the turbine appears at 41 and carries the wheels 42, 43 and 44 with the blades 45, 46, 47 and 48. The wheel 43 corresponds with Fig. 3. The disks 49 and 50 hold the stationary blades 51, 52, 53 and 54. The steam enters through the nozzles 55, passes the impulse blade row 56 and then the reaction blading 51, 52, 53 and 54. The axial thrust of the reaction blading is balanced by the labyrinth disc 57. 58 represents the housing of the turbine.

Obviously, my invention is not restricted to rotary machines of the specific form illustrated, but for example may be used with wheels along which the working medium flows in the same direction on both sides, but with different temperature. Or the one side of the wheel may carry blades, the other side labyrinth packing.

The turbine wheel shown in Fig. 5 represents a simplified construction for high pressure. The wheel 61 carries the blades 62 and 63 with the carrier rings 64 and 65 which are cut from the material of the disk halves 66 and 67. At the inner circumference of the half 66 a special ring 68 is cut from the material of the disk, such ring extending in the same direction as the rings 64. An additional ring 69 runs parallel to the ring 68 in the same direction and is cut from the material of the half 67. Both rings 68 and 69 are united at their ends by shrinking 68 on 69. The ring 68 is made thinner and more elastic than the rings 64, the ring 69 thicker and stiffer than the rings 65. The ring 69 may thus reinforce the whole assembly. The joint between the rings 68 and 69 at their ends is the only contacting area in axial direction between the two disk halves along the at least half the radius thus allowing for free expansion of the rings 68 and 69. The whole assembly is supported by means of the flexible ring 70.

I claim:

1. A blade carrying disk for radial flow rotary machines, in particular steam or gas turbines, having axially extending rings formed by grooves cut into the body of the disk down to a certain residual depth and carrying blades at the outer ends, the disk being supported at the inner diameter, and being provided with an insulating space extending radially through the disk in the region covered by said axially extending rings, said space being open at the periphery of the disk throughout substantially the whole extent thereof and acting to diminish the temperature drop between the bladed ends and the roots of

the rings by throttling the flow of heat from the one side of the disk to the other side.

2. A disk according to claim 1, wherein the disk is supported by an elastic member, thereby permitting the disk to expand and contract or to take an oblique position, the cross section of the circumference of the elastic member being of circular shape with at least one end running at an angle of less than 45° to the radial direction.

3. A disk according to claim 1, wherein parallel to a ring cut from the circumference from one disc half and extending in the same direction as the carrier rings of such disk half, an additional ring runs in the same direction from the other disk half, the ends of such two rings being united with one another.

4. A disk according to claim 1 wherein the disk is supported by an elastic member, thereby permitting the disk to expand and contract or to take an oblique position, the cross section of the elastic member being of circular shape with at least one end running at an angle of less than 45° to the radial direction, the elastic member being constructed and arranged to allow simultaneously for small movements in the axial direction.

5. A blade carrying disk for radial flow rotary machines, in particular steam or gas turbines, having axially extending rings formed by grooves cut into the body of the disk down to a certain residual depth and carrying blades at the outer ends, the disk being supported at the inner diameter, the disk having a slot extending radially through the disk in the region covered by said axially extending rings and cut from the outer circumference of the disk down to the hub along approximately the central plane of the disk, the space formed by such slot acting to diminish the temperature drop between the bladed ends and the roots of the rings by throttling the flow of heat from the one side of the disk to the other side.

6. In a radial flow turbine, the combination with the housing and inlet and outlet passages for a hot driving medium, of a blade carrying disk so arranged in the housing that it is exposed to different temperature conditions upon opposite sides thereof, said blade having axially extending rings formed by grooves cut into the body of the disk down to a certain residual depth and carrying blades at their outer ends, the disk being supported at its inner diameter, and being provided with an insulating space extending approximately radially through the disk along at least part of the region subtended by the axially extending rings, said space being open at the periphery of the disk throughout substantially the whole extent thereof, and acting to diminish the temperature drop between the bladed ends and the roots of the rings by throttling the flow of heat from the one side of the disk to the other side.

ULRICH MEININGHAUS.
